DISPLAY HANGER

Joseph M. Gindi, 4 Morgan Ave., Deal, N.J. 07723

Filed Aug. 26, 1974, Ser. No. 500,715

Term of patent 14 years

Int. Cl. D6—08

U.S. Cl. D6—248

FIG. 1 is a front perspective view of a display hanger showing my new design; and

FIG. 2 is a rear perspective view thereof.

I claim:

The ornamental design for a display hanger, as shown.
